UNITED STATES PATENT OFFICE

2,612,356

HOMOGENIZING DEVICE

Alfred Gerhard Borck, Tullinge, Sweden, assignor
to Aktiebolaget Separator, Stockholm, Sweden,
a corporation of Sweden

Application May 9, 1951, Serial No. 225,291
In Sweden May 12, 1950

20 Claims. (Cl. 259—96)

1

This invention has to do with homogenizing liquids, and particularly with an improved device for this purpose.

Homogenizing requires energy. For a long time it has been the common practice to force the liquid, which is to be homogenized, under high pressure (up to several hundred kgs./cm.²) through a slot, often consisting of a spring-loaded valve and its seat. It was thought that the degree of homogenization depended primarily on the pressure, so that in order to improve the homogenization the first thing to do was to increase the pressure. Latest experience, however, shows that it is possible to obtain with a much lower pressure as good an homogenization as that obtained with the higher pressure used in the prior homogenizing devices. For example, a so-called whirl chamber has been used, often combined with a cyclone, in order to achieve a high turbulence or other whirling movement of the liquid and thereby obtain a very fine atomization, as disclosed in Zachariassen application Serial No. 92,774, filed May 12, 1949. Even better results have been obtained with other devices. For example, very good results have been obtained by driving the liquid through a set of balls, as disclosed in Borck et al. application Serial No. 193,858, filed November 3, 1950, now Patent 2,583,206, dated January 22, 1952. It has become evident that it is not the high pressure which is primarily decisive, but the nature of the homogenizing device. If the liquid is driven into a whirl chamber at a high speed, particularly from a cyclone, by means of which the liquid stream is set in rotation, a good homogenizing result is obtained with the use of a considerably lower pressure than that previously employed in prior homogenizing devices. Homogenizing members of other types, for example, chambers containing bodies of a suitable shape, such as filings, have also yielded good results with relatively low pressures.

In connection with the homogenizing, a treatment in a centrifugal separator is often carried out, as in the case of homogenizing milk. In this case, it is desired to purify the milk in connection with the homogenizing, and the purifying operation is preferably effected in a centrifuge. It is also advantageous to separate the skim milk prior to the homogenizing, so that only the cream has to be passed through the homogenizing device, whereupon cream and skim milk are remixed. In this way a considerable saving of energy is made possible.

It is often desirable to standardize the milk

2

in connection with the homogenizing. By the standardization, a certain predetermined fat content is given to the milk, and this operation is effected in connection with the centrifuging by conducting away a part of the cream or a part of the skim milk while the main part of the cream and the skim milk are remixed to form consumption milk. The present invention makes it possible to conduct away the cream to effect a standardizing in connection with the homogenizing and centrifuging, in an economical manner.

In a centrifugal bowl, the liquid under treatment has the same angular velocity as that of the bowl. Some distance from the axis of rotation this velocity and the static pressure existing there involve a considerable amount of energy. When the liquid is discharged by means of a paring device, the velocity energy may be converted into pressure energy in the paring device. In addition, there exists the static pressure prevailing at the inlet of the paring device. Thus, it is possible to bring about a considerable conversion of energy in the paring device. According to the invention, this fact is utilized to ensure a good homogenizing. This may be achieved by providing the paring device with a suitable homogenizing member, for example, a whirl chamber (together with a cyclone, if necessary) or with a set of balls. In this case, a super-pressure is generated in the inlet of the paring device, by which the liquid is forced through the homogenizing member. It is also possible to utilize more directly the flow velocity of the liquid. The liquid may, for example, flow at unchanged velocity into a cyclone communicating with the paring device and then into a whirl chamber also communicating with the paring device.

The present invention is characterized principally by a rotating container arranged to force the liquid contained in it to partake in its rotation, and by a discharge member projecting into the liquid during operation, in the form of a paring disc, for example, and by a homogenizing device connected with the discharge member or formed therein. A construction of this type may be used for homogenizing without centrifuging but it may also to advantage be built into a centrifugal bowl in which the liquid is subjected to some other treatment in connection with the homogenizing, for example, separation or purification or both.

The accompanying drawings show by way of example some embodiments of the invention. Fig. 1 is a vertical axial sectional view through

an homogenizing device made according to the invention; Fig. 1A is a horizontal sectional view of part of the paring disc in Fig. 1; Fig. 2 is an axial sectional view of a centrifugal bowl, made according to the invention, provided with a paring disc to effect the homogenizing and with a second smaller paring disc for discharging the treated liquid from the bowl; Fig. 3 is a similar view of another embodiment in which the centrifugal bowl is also provided with a paring member for the homogenizing but in which the outlet of the treated product is hermetically connected to the centrifugal bowl by a collar; Fig. 4 is an axial sectional view of a paring member designed for homogenization; Fig. 5 is a plan view, partly in section, of a modified form of the paring disc; Fig. 6 is an enlarged vertical sectional view of the nipple in Fig. 1; and Figs. 7, 8 and 9 are vertical sectional views of further modifications.

According to Fig. 1, the liquid to be homogenized is fed through a fixed pipe 1 into a receiving chamber 2 in a rotatable annular housing or rotor 60 supported by a vertical shaft 61. The housing 60 forms a paring chamber, defined by a lower part 62 fixed to the shaft 61, and an upper part 63 secured to the lower part and forming a cover. From the receiving chamber 2 the liquid is conducted through a number of channels or bores 67 into a circular paring chamber 68 enclosing a paring member 37-38. Radial wings 69 are fixed to the part 63 above the paring member. The tube 1 carries the paring member, which consists of lower and upper annular parts 37 and 38, respectively. The upper part 38 is provided with a depending peripheral flange 39 surrounding an upwardly extending peripheral flange 40 of the part 37. In the flange 39, a number of nipples or pins 41 are inserted which project radially some distance outside the part 38. During operation, the outer part of the paring member 37-38 is enclosed in a rotating liquid. It is desirable that the free surface of the rotating liquid, which is cylindrical, be positioned outside the flange 39, so that only the nipples 41 project into the liquid. Any friction between the rotating liquid and the stationary parts 37-39 is thereby avoided. On the other hand, a relatively large quantity of air follows the liquid into the paring member 37-38 through its inlets 41a (Fig. 6), which are positioned in the nipples 41. In some cases it may therefore be advisable to allow the rotating liquid to more or less overlap the paring disc 37-38 or the flanges 39 and 40. With this overlapping there will, however, be a considerable friction between the rotating liquid and the stationary paring member. This friction, in turn, entails a considerable (sometimes intolerable) heating of the liquid under treatment, and also a corresponding large consumption of energy to operate the apparatus. It is therefore desirable that the level of the liquid be situated wholly outside the flange 39, so that only the nipples 41 project into it during operation. In order to avoid the admixture of air referred to when the level is positioned as described, it is desirable to use streamlined nipples 41.

Each nipple 41 contains a radially cylindrical chamber 42 arranged to form a cyclone together with an inlet to the chamber. The inlet consists of an opening in the form of a narrow slot 41a positioned tangentially in relation to the chamber 42 and having its orifice directed against the direction of movement of the liquid, as indicated

by the arrow in Fig. 6. A whirl of the cyclone type is thus formed in chamber 42. The liquid leaves the chamber, through a central opening 43, in the form of a rotating liquid jet which penetrates into an inner whirl chamber 44 between the paring members 37-38. In the neighborhood of the opening 43, the chamber 44 is provided with a discharge channel 45 which conducts the liquid via another channel 45a into a central chamber 46 which, by a channel 64 enclosing the pipe 1, communicates with an outlet for the homogenized liquid from the paring device. The paring disc is provided with any desired number of circumferentially spaced nipples 41 with whirl chambers of the type described.

The feed tube 1 is supported by a part 65 which during operation is fixed to a frame (not shown) by a hood 66.

Referring to Fig. 5, the paring member there shown comprises a disc 48 provided with one or more segments 49 each having a cyclone chamber 42a. The whirl chamber 44a communicating with the chamber 42a is positioned in the main part of the paring disc 48 and consists of a radial bore therein. The channel 45a is formed by a space between the parts 48 and 49. This space also contains a packing 50. The channel 45a connects the outer portion of whirl chamber 44a with the chamber 46 by way of channel 51. The tangentially directed inlet 41a of chamber 42a ends at the lower side of the segment 49. With this design, the rotating liquid must overlap the outer part of the paring member 48 and the segment 49, to reach the inlet 41a to the cyclone chamber 42a. The paring member is provided with one or more segments 49, according to the quantity of liquid to be homogenized.

Referring to Fig. 2, the liquid to be homogenized is fed through a fixed pipe 1a into the receiving chamber 2a of a centrifugal bowl or rotor B which is provided with radial wings 3 by which the incoming liquid is caused to follow the rotation of the bowl. From chamber 2a, which is positioned in a distributor 5, the liquid proceeds through a number of channels 6 into a set of conical discs 7 in which it is separated in the usual manner into a lighter component flowing inward toward the rotation axis, and a heavier component flowing outward toward a sludge space 8. The lighter component discharges through an annular channel 9 between a top disc 10 and the distributor 5 into a paring chamber 11. The latter is provided in the usual manner with radial wings 12 and 13 rotating with the bowl and positioned above and below a stationary paring disc 14 in chamber 11, the disc 14 being supported by the inlet pipe 1a. After having entered the paring disc 14 and having been homogenized therein by a suitable device (for example, by the arrangement illustrated in Fig. 5 and including the cyclone chamber 42a and whirl chamber 44a), the lighter component is led back through channels 15 into the receiving chamber 2a in which it is mixed with the liquid delivered through pipe 1a.

When homogenizing a liquid incident to its discharge from the paring chamber 11 by means of the paring disc 14, the particles or drops of the liquid to be atomized are split up into a much greater number of particles or drops which, however, vary considerably in size. When these drops or particles enter the set of discs 7, the smaller particles follow the heavier liquid component outwardly, whereas the larger accompany the lighter component inwardly and are there-

fore again subjected to the atomizing process in paring disc 14.

The heavier component is collected in the sludge space 8 whence it proceeds through another set of conical discs 16 inward into a collecting chamber 17 and then through a channel 18 outside the paring chamber 11 into a smaller paring chamber 19 positioned above the chamber 11 and containing another smaller paring disc 20 which is also supported by the pipe 1a. The paring chamber 19 is provided with rotating radial wings 21 and 22 positioned above and below the paring disc. The paring disc 20 is provided with a number of channels 23 extending from the periphery inward and communicating with axial channels 24, which extend upward through the rotor outlet 8a to a fixed discharge pipe 25.

The pipe 1a is fixed to a stationary part 26 forming a hood (illustrated in part) which covers the centrifugal bowl. The pipe 1a is secured to the part 26 by a nut 27 forming one-half 28 of a coupling, the other half of which is fixed to a feed pipe (not shown).

When treating milk, for example, in this centrifuge for homogenization and purification, the primarily lighter component separated between the discs 7 is led via passage 9 and chamber 11 through the larger paring disc 14 comprising the homogenizing device 42a—44a, and thence through passage 15 to join the feed to the centrifuge. The heavier component, the amount of which is usually larger, is conducted via disc set 16, channel 18 and chamber 19 to the smaller paring disc 20, by which it is discharged from the centrifugal bowl. The product thus discharged contains the entire fat content of the milk fed into the centrifuge, although in so finely divided form that the fat cannot be separated through the centrifugal force but follows the heavier component. This applies to conditions prevailing when a state of permanency has been attained. The device operates with recirculation of those fat drops or balls which were unsufficiently split up during the first homogenization. The separating effect in the discs 7 ensures that all particles or drops over a certain size, for example, 0.8μ , are prevented from following the milk current discharging outward in the discs 7 and further through the discs 16 and the paring disc 20 from the centrifugal bowl.

The embodiment illustrated in Fig. 3 is characterized in that the homogenizing paring disc has an outward outlet, as contrasted with the embodiment shown in Fig. 2. In this case the liquid to be treated is assumed to be fed in through passage S¹ in the centrifuge spindle S at the lower part of the bowl 8. As in Fig. 2, this liquid is first conducted to the set of discs 7 in which it is separated into a lighter and a heavier component. The lighter component passes inward to the central part of the bowl from which it is led through channels 30a and 30 into paring chamber 11 which may be identical with that shown in Fig. 2. Thus, it is provided with radial wings 12 and 13 positioned above and below a paring disc 14. The latter includes an homogenizer which may be identical to the homogenizing arrangement 42a—44a illustrated in Figs. 2 and 5. From the paring disc 14, the homogenized liquid flows through a system of discharge passages 31 into a fixed return pipe 32, the continuation of which (not shown) communicates with the feed pipe S¹ of the centrifuge along a return path 32a. The homogenized liquid is herein mixed with the untreated liquid and then reintroduced into the set of discs 7, in which insufficiently atomized parti-

cles or drops are separated and follow the lighter component inwardly and are again treated in the homogenizing device of the paring disc 14. The sufficiently atomized drops or particles follow the heavier component into the sludge space 8 and proceed into a purifying set of discs 16 and then into a central outlet tube 32 and into a fixed discharge pipe 34 connected to the outlet pipe 33 by a packing collar 35. Outside the orifice of the pipe 33 is a pump wheel 36 rotating with the centrifugal bowl and serving to generate a higher pressure in the discharge pipe 34. If desired, some of the liquid may be withdrawn from pipe 32a to effect standardizing of the fat content of the liquid treated in the centrifuge, as by means of a branch pipe 32b having an adjustable valve 32c.

In Fig. 4, I have shown a paring disc suitable for use in the apparatus of Fig. 2. It is substantially similar to the paring member 37—38 shown in Fig. 1. However, the homogenized liquid is conducted from chamber 46 through channels 47 downward into the channels 15 and chamber 2a (Fig. 2).

In Fig. 7, I have shown a paring disc provided with an homogenizing device and differing from that of Fig. 1 mainly in that the common axis of the cyclone chamber 42b and the whirl chamber 44b is parallel with the rotation axis of the bowl or rotor 60b instead of perpendicular to it. The paring disc 72 is supported by the feed pipe 1b and has at its periphery a number of cylindrical chambers 42b provided with tangentially directed inlet channels 71, arranged in a manner similar to that of Fig. 6. The inlet 71 forms a narrow slot, the orifice of which is rectangular and positioned at the outer cylindrical surface of the paring disc. The liquid passes through the central outlet 43b of the chamber 42b into the whirl chamber 44b and then back into a channel 45 and further through channels 64b to the outlet. The paring chamber 68 is provided with conveyor wings 69 and 70 arranged in the rotatable housing 60b and forcing the liquid arriving through pipe 1b and chamber 2b to partake in the rotation of the housing 60b.

In the homogenizing device illustrated in Fig. 8, the paring disc is provided with a homogenizing member in the form of a set of balls 75 forming constricted passages for the liquid. The pipe 1c carries a disc-shaped part 73 comprising a chamber 42c, the inlet orifice 74 of which is positioned in the outer part of the lower side of the disc 73. The inlet 74 is positioned tangentially in relation to the generally radial chamber 42c, so that a rotating body of liquid is formed in the chamber during operation. The chamber communicates in its inner part with an homogenizing chamber containing a plurality of the closely packed balls 75, all of which are of the same size. The wall 76 of the ball chamber projects only a short distance into the chamber 42c so that the rotation of the liquid is not substantially impaired. The wall is provided with an oblong slot 77, the longitudinal direction of which is parallel with the direction of flow of the liquid. The liquid gradually flows through this opening into the set of balls 75 and passes between the balls to an outlet 78 and further through channels 79 and 64c. The paring disc may be provided with any arbitrary number of such chambers 42c and chambers for the balls 75.

In order that a homogenized product shall remain stable, it is very important that the smaller units formed by division of larger particles or

drops rapidly come into intimate contact with every part of the surrounding liquid. By the division, the contact surface between the drops or particles and the liquid becomes larger, which is favorable with regard to the chemical and physical equalization upon which the stability depends. But it is nevertheless very important that the different parts of the treated liquid are rapidly and intimately mixed with one another and that the contact between the membranes of the drops or particles and the liquid in which they are dispersed becomes as good as possible.

According to the invention, the homogenized liquid may for this purpose be subjected to a stabilizing after-treatment following immediately upon the homogenization. It consists substantially of an intense agitation of the various parts of the liquid. This effect may be brought about by a whirl chamber of the same type as that used for the homogenization. A device for this purpose is illustrated in Fig. 9. The homogenized liquid issuing from the outlet 64, 25 or 34 of Figs. 1, 2 and 3, respectively, is conducted to an inlet 80 of the stabilizing device of Fig. 9. From this the liquid flows through a nozzle 81, the through-flow area of which may be regulated, into a whirl chamber 82 and then through an outlet 83 positioned close to the nozzle 81 and through which the liquid leaves the apparatus. The throughflow area of the nozzle 81 may be regulated by a spindle 85 with a tapered end arranged to be moved axially by a wheel 86 so as to make it fill up the opening of the nozzle 81 more or less. This after-treatment generally requires a pressure of only a few kilograms, whereas up to 13 kilograms are required in the homogenizing paring disc.

Regarding the cyclone shown in Fig. 6, the slot-shaped inlet opening may be directed forward right against the direction of flow of the rotating liquid. Experiments have shown, however, that a better result is sometimes attained when the inlet opening has another direction, for example, is directed backward or at right angles to the direction of flow or at a suitable obtuse or acute angle to the direction of flow. It may also be desirable to arrange the orifice of this inlet in a projection, or the like, of the paring disc itself. In this way, an overlapping of the paring disc proper is avoided, so that the friction between the paring device and the rotating liquid is reduced.

It will be understood that the homogenizer 44, 44a, 44b or 75, as illustrated in Figs. 1, 2, 4, 5, 7 and 8, is formed in effect by the respective paring discs, the outer parts (41, 49, etc.) of which form the paring member whereby the liquid is withdrawn in a jet from the rotating liquid annulus in the rotor and passes under pressure to the homogenizer.

I claim:

1. An homogenizing device comprising a hollow rotor having an inlet for the liquid to be homogenized, means in the rotor for causing the liquid therein to partake of the rotation of the rotor, whereby the liquid forms an annulus in the rotor, a paring member having an inlet opening positioned to project into the inner surface of said annulus and also having a discharge channel extending through said member, and an homogenizer communicating with the inlet opening of the paring member and situated in said discharge channel to receive liquid pared from said annulus.

2. A device according to claim 1, in which the

homogenizer forms a whirl chamber communicating with said inlet opening for receiving a liquid jet therefrom, the whirl chamber being open at one end to receive said jet and discharge the liquid from the chamber, the other end of the chamber being closed, whereby the liquid from said jet is deflected about 180° in the chamber.

3. An homogenizing device comprising a hollow rotor having an inlet for the liquid to be homogenized, means in the rotor for causing the liquid therein to partake of the rotation of the rotor, whereby the liquid forms an annulus in the rotor, a paring member having an inlet opening positioned to project into the inner surface of said annulus, and an homogenizer forming a whirl chamber communicating with said inlet opening for receiving a liquid jet therefrom, the paring member having a cyclone chamber affording communication from said inlet opening to the whirl chamber, said inlet opening being disposed generally tangentially relative to the cyclone chamber.

4. A device according to claim 3, in which the paring member includes a nipple containing said cyclone chamber and inlet opening and projecting outside the main portion of said member, so as to extend into the liquid annulus.

5. A device according to claim 3, in which the homogenizer is formed by the paring member, said whirl and cyclone chambers being disposed in the outer part of the paring member and having a common axis of symmetry extending substantially radially of the rotor.

6. A device according to claim 3, in which the homogenizer is formed by the paring member, said whirl and cyclone chambers being disposed in the outer part of the paring member and having a common axis of symmetry extending substantially parallel to the rotor axis.

7. A device according to claim 3, in which the paring member is circular and has a peripheral segment forming the cyclone chamber and inlet opening, the whirl chamber being located between said segment and the rotation axis of the rotor.

8. An homogenizing device comprising a hollow rotor having an inlet for the liquid to be homogenized, means in the rotor for causing the liquid therein to partake of the rotation of the rotor, whereby the liquid forms an annulus in the rotor, a paring member having an inlet opening positioned to project into the inner surface, the paring member having an homogenizing chamber communicating with said opening to receive liquid therefrom, and a series of balls filling said chamber to form constricted passages for the liquid.

9. A device according to claim 8, in which the paring member forms a cyclone chamber having its rotation axis disposed generally radially of the rotor, said inlet opening extending into the cyclone chamber substantially tangentially thereof, the cyclone chamber extending from the outer part of the paring member to the homogenizing chamber.

10. A device according to claim 8, in which the paring member forms a cyclone chamber having its rotation axis disposed generally radially of the rotor, said inlet opening extending into the cyclone chamber substantially tangentially thereof, the cyclone chamber extending from the outer part of the paring member to the homogenizing chamber, the homogenizing chamber being cylindrical and having its axis substantially parallel with said rotation axis of the cyclone

chamber, the homogenizing chamber having a wall projecting into the cyclone chamber and provided with a peripheral slot connecting said chambers.

11. A device according to claim 8, in which the paring member form a cyclone chamber having its rotation axis disposed generally radially of the rotor, said inlet opening extending into the cyclone chamber substantially tangentially thereof, the cyclone chamber extending from the outer part of the paring member to the homogenizing chamber, the homogenizing chamber being cylindrical and having its axis substantially parallel with said rotation axis of the cyclone chamber, the homogenizing chamber having a wall projecting into the cyclone chamber and provided with a peripheral slot connecting said chambers, the homogenizing chamber also having an outlet opening in a wall thereof nearest the rotor axis.

12. An homogenizing device comprising a hollow rotor having an inlet for the liquid to be homogenized, means in the rotor for causing the liquid therein to partake of the rotation of the rotor, whereby the liquid forms an annulus in the rotor, a paring member having an inlet opening positioned to project into the inner surface of said annulus, the rotor having a centrifugal separating chamber and also a paring chamber containing said member, there being a passage in the rotor leading from the inner portion of the separating chamber to the paring chamber for conducting thereto a lighter separated component, and an homogenizer supported in the rotor and communicating with said inlet opening for receiving liquid therefrom.

13. A device according to claim 12, in which the paring member has a recycling passage leading from the homogenizer and communicating with the separating chamber for returning homogenized liquid thereto.

14. A device according to claim 12, in which the rotor has an outlet communicating with the outer portion of the separating chamber for discharging a heavier separated component, the rotor also having a purifying chamber through which the heavier component passes on its way to said outlet, and a set of conical discs in said purifying chamber.

15. A device according to claim 12, in which the rotor has an outlet communicating with the outer portion of the separating chamber for discharging a heavier separated component, the rotor also having a purifying chamber through which the heavier component passes on its way to said outlet, a set of conical discs in said purifying chamber, the rotor also having a second paring chamber and a passage outside the first paring chamber for leading the heavier component from the purifying chamber to the second paring chamber, and a second paring member in said last paring chamber for discharging liquid therefrom through said outlet, the second paring member being of smaller diameter than said first member.

16. An homogenizing device comprising a hollow rotor having a centrifugal separating chamber and also having a paring chamber commu-

nicating with said first chamber for receiving a separated liquid component therefrom, a feed pipe leading into the rotor for supplying liquid to the separating chamber, a paring member in the paring chamber having an inlet opening positioned to extend into the inner surface of a rotating liquid annulus in the paring chamber, an homogenizer supported by the paring member and having a discharge passage leading from the rotor, and a return pipe outside the rotor for connecting said discharge passage to the feed pipe, whereby liquid from the homogenizer is recycled to the separating chamber.

17. A device according to claim 16, comprising also a branch pipe leading from said return pipe to withdraw liquid therefrom, and a valve in the said branch pipe for regulating the amount of said withdrawal.

18. A device according to claim 16, in which the rotor also has an outlet for a heavier component separated in said separating chamber, the rotor also having a purifying chamber affording communication between the outer portion of the separating chamber and said outlet, a set of conical discs in said purifying chamber, a fixed discharge pipe leading from the outlet for said heavier component, and a central tube in the rotor connecting said purifying chamber with the fixed pipe through said outlet.

19. A device according to claim 16, in which the rotor also has an outlet for a heavier component separated in said separating chamber, the rotor also having a purifying chamber affording communication between the outer portion of the separating chamber and said outlet, a set of conical discs in said purifying chamber, a fixed discharge pipe leading from the outlet for said heavier component, a central tube in the rotor connecting said purifying chamber with the fixed pipe through said outlet, a packing collar making a tight joint between the central tube and said fixed discharge pipe, and a pump wheel on the central tube for generating an increased pressure in the fixed discharge pipe.

20. A device according to claim 1, in which the device has an outlet leading from the homogenizer, a stabilizing device communicating with the outlet and including a whirl chamber, and an adjustable nozzle controlling flow of homogenized liquid through said last chamber.
